MIXING DEVICE

Joseph Wolfson, Hartford, Conn.

Application February 26, 1947, Serial No. 731,152

8 Claims. (Cl. 299—84)

1

The present invention relates to improvements in mixing devices and more particularly relates to an improved mixing device adapted to mix into a stream of water or other liquid a material which may be soluble in that liquid, for instance mixing into a water stream material such as soap, liquid or powder, DDT powder, and any degreasing compounds, or liquids such as may kill weeds, or any type of powder poison used for plants and gardening.

The invention has for an object to produce an improved mixing device which will positively entrain desirable quantities of the material in the liquid stream with a nice regulation thereof.

Another object of the invention is to provide an improved mixing device in which an improved form of float valve adjustment and suspension is provided whereby the regulation and admission of the mixture to the liquid stream is more nicely controlled than heretofore.

Other objects of the invention are to reduce the cost of the mixing material by nice regulation and proper distribution thereof, to insure uniformity of distribution of the mixture throughout the liquid stream so that uniform results may be anticipated from separating and the like continuous operations, and wherein the mixing device itself is of an extremely simple mechanical form and inexpensive in its construction and retail cost while being compact in size and efficient in operation.

With the foregoing and other objects in view, the invention will be more fully described hereinafter and more particularly pointed out in the appended claims.

In the drawings, in which like parts are denoted by the same reference characters throughout the several views,

Figure 1 is a side elevation of an improved mixing device constructed in accordance with the present invention and shown as connected in a liquid distribution line, partly broken away.

Figure 2 is a top plan view of the improved mixing device taken on an enlarged scale.

Figure 3 is a transverse vertical section taken on the line 3—3 in Figure 2.

Figure 4 is a longitudinal central vertical section taken on the line 4—4 in Figure 2.

Referring more particularly to the drawings, 10 and 11 designate inlet and outlet branches which together with a right angle branch 12 are all made preferably from a T-casting. The branches 10 and 11 may be in axial alignment and in the single embodiment shown in the drawings are arranged horizontally.

Threads 13 and 14 on the outer ends of the

2

branches 10 and 11 provide for receiving standard hose couplings of sections of hose indicated in broken lines at 15 and 16 in Figure 1. The hose section 15 is connected between the inlet branch 10 of the mixing device and a faucet or other source of water or other liquid supply 17. The outlet hose section 16 is broken away as indicating that it extends to any desired destination.

In the inlet branch 10 is a tapered bore 18 to decrease volume and increase the rate of flow substantially after the manner of a Venturi tube.

The upstanding branch 12 constitutes an inlet for the mixture of material which is received from a funnel 19 welded or otherwise connected to the upper end of the hollow branch 12 and interiorly opening into the same. The funnel 19 may be of suitable size to hold a quantity of powdered or liquid material. Across the upper portion of the funnel extends an arched brace 20 having its downturned flanged ends bolted as indicated at 21 to diametrically opposite side wall portions of the funnel 19. Of course the ends of the brace 20 might be welded to the funnel or attached thereto in any other desired manner.

A threaded tension bolt 22 is threaded through a central portion of the brace 20 or through a nut 23 welded or otherwise secured to the brace 20 which is perforated in alignment with the nut 23 to permit the passage of the tension bolt 22 which may thus be raised and lowered by rotating the same in the one or other direction. The lower end of the bolt 22 carries a helical or coil spring 24 the lower end of which is connected to one end of a chain 25 or other flexible connection. A ball valve 26 is affixed to the lower end of the chain and normally hangs by gravity in a position in the upstanding branch 12 substantially below the valve seat 27 at the lower end of the funnel 19 where the end of the funnel extends downwardly and inwardly of the upper portion of the vertical wall of the upstanding branch 12. The valve 26 is a float valve and is preferably made of cork of a diameter less than the diameter of the upstanding branch 12 whereby the material in the funnel 19 may descend past the valve 26 downwardly through the neck or branch 12 and into the stream of liquid flowing through the horizontal branches 10 and 11.

The parts heretofore described may be mounted in a case 28 of suitable material, for instance sheet metal or plastic and metal or other braces 29 may serve to hold the mixing device in a proper position in the case with the upper end of

the funnel 19 open to receive the material and with the threaded ends 13 and 14 of the horizontal branches 10 and 11 exposed for receiving the pipe couplings. Of course it will be understood that the ball valve 26 may be made of plastic or hollow metal. It is governed in its action by the tension screw 22 and the presence or absence of water in the upstanding branch 12. When the water is shut off at the tap or spigot 17, the water will back up in the upstanding branch 12 and float the ball 26 up against the seat 27, thus preventing water from entering the funnel 19 and diluting the mixture therein. The flexible chain 25 permits the ball 26 to rise to the seat 27 in obedience to flood conditions in the upstanding branch 12 irrespective of the fixed adjustment of the screw bolt 22. When flood conditions subside the ball 26 may drop by gravity to the open position as shown in Figure 4 and the coil spring 24 will cushion this fall. This spring 24 adds tension to the float ball 26.

In use, the substance to be mixed with the liquid is placed in the funnel 19. Regulation is by rotating the screw 22 to raise or lower the ball 26 with reference to the seat 27. The position of the ball 26 is dependent upon the type of substance used, that is whether it is powder or liquid. If the substance is liquid, the port area opened by the adjustment of the ball 26 is small so that liquid will drop through the opening without the aid of any added pressure. If the substance is powder, a larger opening is required to reduce resistance to the flow of the powder into the T-casting.

The flow of water through the tapered bore 18 causes an air suction in the open end of the funnel orifice, causing a mixture of substance and air to bring the pressure up to the original faucet pressure or greater than the faucet pressure. This device is attached either to the faucet 17, if convenient, or a few feet from the faucet by a small length of hose 15. It is better practice to place the mixing device as close to the faucet 17 as practicable, owing to the fact that this yields a longer hose line 16 in which every opportunity is given the substance to mix with the water en route to its destination. When the water is shut off at the nozzle end the water will press the float ball 26 up against the funnel seat 27 and keep the water from mixing with the substance in the funnel and cause complete shut off of water.

The improved device may be used for washing automobiles, or for spraying water and DDT mixture on plants. It may also be used for spreading substances soluble in water on plants or other surfaces. It can be used by gas stations for car washing and spreading degreasing mixture on the grease spots of garage floors or under lifts. It may be used for cleaning tanks in degreasing units of plating and painting plants by filling the funnel with degreasing compound and attaching to a water unit for filling the tank. The compound will enter with water.

While I have disclosed herein the best form of the invention known to me at the present time, I desire it to be understood that I reserve the right to make changes and modifications in the herein described embodiment of the invention provided such changes fall within the scope of the following claims.

What I claim is:

1. A mixing device comprising a liquid flow line having a tapered section therein, an upstanding neck connecting with the line just beyond the

smaller end of said tapered section, a receptacle for a mixing substance communicating with said upstanding neck and having a valve seat on its lower end projecting into the upper portion of said neck, a brace carried by said receptacle at its upper portion, a float valve movably mounted in said neck, and adjusting and suspending means for said valve hung from said brace to gravitationally suspend the float valve in an open position spaced below said valve seat.

2. A mixing device as claimed in claim 1 characterized by the fact that the adjusting and suspending means comprises a screw threaded in said brace and a flexible connection between said screw and valve.

3. A mixing device according to claim 2 wherein a coil spring is interposed between the screw and the flexible connection.

4. A mixing device according to claim 3 in which said brace is arched or bowed upwardly to raise the same and the adjusting screw above any material in the receptacle.

5. A mixing device as claimed in claim 4 in which the receptacle is a funnel open at its upper end to receive the substance and welded or otherwise affixed to the upper end of the upstanding neck throughout a circular area spaced above the lower end of said funnel which constitutes the valve seat.

6. A mixing device comprising substantially aligned inlet and outlet branches, said inlet branch having a tapering bore substantially in the form of a frustum of a cone, a substantially vertical hollow neck upstanding from the inlet and outlet branches at the meeting point of the same, said neck being disposed at the smaller end of the tapering bore, a funnel for the substance to be mixed carried by the upper end of said upstanding neck and communicating with said neck and having a valve seat in its lower end, a float valve of smaller diameter than the internal diameter of the neck movably mounted in said neck and adapted to close against said valve seat, a flexible connection carrying said ball valve, an adjusting screw carrying said flexible connection, a resilient member connected between said screw and flexible connection, a bowed brace spanning the upper portion of said funnel and threadedly receiving said bolt at a central high portion, and a case extending about said inlet and outlet branches, upstanding neck and funnel.

7. A mixing device as claimed in claim 6 characterized by the fact that the case is open to reveal the opening in the wide portion of the funnel and the inlet and outlet branches have free threaded ends which extend beyond the case for taking standard hose couplings.

8. A mixing device as claimed in claim 7 in which straps are connected to the case and to the inlet and outlet branches for orienting the mixing devices in said case.

JOSEPH WOLFSON.
